FISHING ROD-HOLDING SAND SPIKE

Frank A. Turiace, Jr., 2820 N. Main St.,
Los Angeles, Calif.

Filed Aug. 11, 1964, Ser. No. 81,243

Term of patent 14 years

(Cl. D31—4)

FIG. 1 is a perspective view of a fishing rod-holding sand spike, showing my new design.

FIG. 2 is an enlarged top plan view thereof.

FIG. 3 is a bottom plan view thereof with portions disclosed above the anchor plate omitted for convenience of illustration; and

FIG. 4 is a rear elevation thereof.

I claim:

The ornamental design for a fishing rod-holding sand spike, substantially as shown and described.
